UNITED STATES PATENT OFFICE.

HENRY W. WANAMAKER, OF BALTIMORE, MARYLAND, ASSIGNOR OF ONE-HALF TO JOSEPH R. WILSON, OF SAME PLACE.

BRICK-KILN.

SPECIFICATION forming part of Letters Patent No. 607,973, dated July 26, 1898.

Application filed January 20, 1898. Serial No. 667,244. (No model.)

To all whom it may concern:

Be it known that I, HENRY W. WANAMAKER, a citizen of the United States, residing at Baltimore city, in the State of Maryland, have 5 invented new and useful Improvements in Brick-Kilns, of which the following is a specification.

This invention relates to certain new and useful improvements in kilns designed for 10 burning high-grade brick, tiles, or other articles made of clay or other material.

The object of my invention is to provide a kiln which is so constructed that the entire 15 heat of the furnaces will be utilized and to provide one which may be kept in continuous 20 operation, the kiln being so constructed that the heat and products of combustion from the furnaces will not be permitted to come in direct contact with the material placed in the 25 kiln to be baked or burned.

A further object of my invention is to utilize 25 the heat given off from the bricks or other products as they are being baked or burned by causing the same to pass into the adjacent 30 oven or ovens, the ovens being provided with flues independent of the heating-flues, by means of which the heat can be carried from 35 the ovens to the stack.

With the above object in view my invention 40 consists in the combination of a series of muffle kilns or ovens, flues arranged in the longitudinal walls of the kilns which will convey the heat and products of combustion 45 from the heat-chambers positioned at the sides and top of the muffle kilns or ovens to the adjoining one, each section having furnaces and flues which connect the heating-chamber with the main flue, which leads to a stack.

The invention also consists in connecting a 50 series of muffle kilns or ovens, each having independent furnaces, with a main flue, so that the bricks or other wares or material placed in the kiln may be burned or baked 55 consecutively or independently.

The invention also consists in connecting the muffle kilns or ovens with each other, so 60 that the heat which is given off from the bricks or other products placed therein and heated will be caused to pass from one muffle kiln or oven to the one adjacent thereto, so as to assist in drying and heating said muffle kiln or oven prior to burning; also, in pro-

viding flues which are independent or disconnected from the flues or chambers through 55 which the products of combustion pass and are connected with the oven and with the flues leading to the stack, so that the ovens may be connected, when desired, with the 60 stack.

The invention further consists in the special construction and arrangement of the flues which are connected with the furnaces and the stack and the flues which connect the muffle kilns or ovens with the stack, as will 65 be hereinafter set forth.

In the practical embodiment of my invention I prefer to provide two longitudinal series of kilns, between which are located a passage and a stack or chimney, and on each side of 70 the stack, parallel with the kilns, is a main flue, having short flues connected with the heat-chambers of the muffle kilns or ovens and with the furnaces. The outer walls of 75 the kiln have built therein flues which connect the adjacent heat-chambers with each other, and the inner or opposite walls of the kiln have built therein flues which connect with flues in communication with the muffle kilns or ovens, the longitudinal flues being 80 connected with the flues leading to the stack, so that the vapor, water, smoke, or steam given off from the products placed in the muffle kilns or ovens may be removed therefrom and carried to the stack. The adjacent 85 side walls of the kilns have doorways opening into the muffle kilns or ovens, and the outer or opposite side walls of each section have a series of furnaces connected with a corresponding series of flues or heat-passages 90 which extend from the furnaces to the heating-chamber surrounding or extending about the sides and top of the oven opposite or adjacent to the particular series of furnaces, each muffle kiln or oven being provided with 95 a short flue which connects the heating-chamber thereof with the main flue of the stack. Each of the muffle kilns or ovens is provided with flues which are separate and independent of the heat-conveying chambers or 100 flues and are connected with horizontal flues in the foundation-walls, the latter communicating with the flues leading to the stack, these flues being provided with dampers, so that a circulation may be established between 105 the muffle kilns or ovens and the stack, dam-

pers being provided, so that said flues can be cut off when desired.

The partition-walls between each of the muffle kilns or ovens and at the end of each series are pierced or apertured, so that the heat from one may pass to the adjoining oven, and so on to the end of the series.

In the accompanying drawings, Figure 1 is a horizontal sectional view of a kiln constructed in accordance with my invention. Fig. 2 is a vertical sectional view taken on the line 2 2 of Fig. 1. Fig. 3 is a vertical section taken on the line 3 3 of Fig. 2, looking toward the stack; and Fig. 4 is a sectional view on the line 4 4, looking in the direction indicated by the arrows.

A refers to the stack, which is connected to the main flues A'. Said flues have a series of branch flues A², which connect with each of the heating-chambers surrounding the muffle kilns or ovens.

B refers to the outer vertical walls of the kiln-sections, which are provided with flues, said flues having horizontal sections b b' and vertical sections b², which are built in the wall and form a part thereof. The outer walls are provided with a series of furnaces C, each section of the series being opposite the muffle kilns or ovens. The ovens are of the usual type, and the openings therefrom are on a line with a corresponding series of arches D, said arches being of the same length as the base or bottom of the muffle-kilns.

The walls of the main kiln adjacent to the passage-way between them have doorways which lead into the muffle kilns or ovens, and the side walls and arched top of the kilns where the heat comes in contact therewith, as well as the flues, are lined with fire-brick, and a suitable system of T-iron braces are used to clamp the side walls.

The flues which connect the heat-chamber surrounding the ovens are provided with dampers a² of any suitable type, they being used for connecting or disconnecting the heating-chambers surrounding the muffle kilns or ovens with the main flues A', and the furnaces are provided with the usual dampers, so that each furnace can be operated independent of the other. The inner side walls of the kiln are provided with flues, as will be hereinafter described, which connect the muffle kilns or ovens with the stack when desired.

Within the side walls of the kilns are built muffle kilns or ovens E, the side walls thereof extending from the flues or arches D upward, parallel with the outer walls of the kiln, they being arched at the top, and at the commencement of the springing of the arch are a series of blocks e, which are separated, so that the heat and products of combustion may pass between the same. The ovens opposite the doorways have openings which form a continuation of said doorways to provide means for access to the interior of the ovens. Between the flues b b' the heat-cham-

bers are intersected by a horizontal wall e'. The kiln or chamber thereof within the outer walls is provided between each doorway with transverse walls E', which extend from the side walls of the oven and intersect the heat-chambers surrounding the same. The transverse walls E' are preferably positioned opposite the vertical flues b², and they are provided with apertures or slits e², through which the heat from one muffle kiln or oven may pass from the one adjacent thereto, and so on throughout the series. The end walls of the kiln are provided with apertures which connect with end flues F F, extending from one of the kiln-sections to the other, and below the aforesaid flues are flues which connect the heat-spaces surrounding the ovens or muffle-kilns with the spaces surrounding the ovens of the adjacent kiln-section.

In the longitudinal foundation-walls of the kiln nearest the stack are formed longitudinal flues G and vertical flues g, which extend upward therefrom and are provided with dampers g', above which are short horizontal flues g², connecting with short vertical flues g³, built in the space between the walls of the ovens and the main inner wall of the kiln on a line with the partition-walls of the oven. Beneath the partition-walls E' and between the arches or flues D are transverse flues G', having openings g⁴ on a line with the openings g³ in the partition-walls. The longitudinal flues G G are connected with the main or branch flues which lead to the stack.

By providing the flues G G and connecting them with the muffle kilns or ovens when desired communication between the ovens and stack can be made, so as to lead directly to the stack such vapors or other products as may be given off from the bricks or other wares in drying them prior to baking or burning, and at the proper time communication can be cut off, so that the heat will be caused to pass from one oven to the next one. The ovens can also be connected with the stack when it is desired to cool one or more of the ovens.

With a kiln constructed as hereinbefore described it will be noted that the dampers may be set so that there will be no connection between the furnaces and the ovens and that the products of combustion and smoke cannot at any time pass into the ovens; also, that the heat may be caused to circulate from one muffle kiln or oven into the adjacent oven in either direction or be led to the stack. A kiln constructed in accordance with my invention may be kept in continuous operation, and the heat in any particular oven or ovens can be regulated by increasing or diminishing the number of furnaces in use.

In operation when the fires in one of the series of furnaces are started the heat and products of combustion therefrom will pass through the flues D at the bottom of the muffle kilns or ovens, pass upward in the heat-chamber thereof over the top of the oven, down-

ward into the horizontal flue b , from thence downward through the flue b^2 into the flue b' , to the heating-chamber surrounding the next muffle kiln or oven, and the heat will be so 5 conveyed until it finds an outlet through one of the connecting-flues A^2 to the main flue leading to the stack. To make connection with the stack, it is only necessary to raise one of the dampers a^2 . As the brick or material in the muffle kilns or ovens is being burned the vapor or moisture given off therefrom can be caused to pass through the apertures or openings g^4 in the bottom walls of the oven, between the openings e^2 , and will 10 be drawn into the transverse flue G' and from thence into the flue G to the stack. After the bricks or material in the ovens has been sufficiently dried out the damper between the flues G G' is closed, and the heat 15 from the oven will pass to the adjacent one. The flues outside of the kiln-sections which connect the ends of the kilns have passages connecting the heat-chambers, as well as passages for connecting the muffle kilns or ovens.

25 What I claim as new is—

1. In a kiln the combination with the outer walls having on one side above the level of the furnaces, flues, ovens forming with the flues heating-chambers each oven having means for 30 establishing communication with the main flue leading to the stack the flues in the side walls establishing communication with the heating-chamber of the adjacent oven for the purpose set forth.

35 2. In a kiln constructed to provide a series of ovens which are adjacent to each other each oven having independent furnaces and independent connection with a flue leading to the stack, a horizontal wall between the wall of the kiln and the oven-flues above said wall connected by a vertical flue, whereby the products of combustion are caused to pass under and around the oven to the vertical flue and from thence to the heating-chamber of the adjacent oven, substantially as shown and for the purpose set forth.

3. In a kiln, the combination with the main, side, and end walls, of a series of muffle-ovens within said walls, furnaces for each oven, 50 flues connecting with the furnaces and opening into a heating-chamber surrounding the oven-flues for connecting said oven with the oven or ovens adjacent thereto and a flue connecting the heating-chamber with a flue which leads to the stack, substantially as shown and for the purpose set forth.

4. In a kiln the combination with the walls inclosing a series of muffle-ovens, the outer walls having for each oven a plurality of furnaces and a corresponding number of horizontal flues connected with a heating-chamber which surrounds the top and sides of the oven, the side wall of the kiln having vertical flues in communication with horizontal flues which extend from the section of the kiln to the sections or muffles adjacent thereto and a horizontal cut-off interposed between

the horizontal connecting-flues, substantially as shown.

5. In a kiln the combination of a horizontal 70 series of muffles or ovens the dividing-walls between the adjacent ovens having apertures therein so that the heat generated in one of the ovens can pass to the adjacent one, substantially as shown.

75 6. In a brick-kiln having a series of muffles or ovens, of openings in the dividing-walls for establishing communication between the ovens, a flue connecting the end series of ovens with the end series of the ovens of another kiln-section, substantially as shown.

7. In a kiln having a series of ovens arranged longitudinally within separate kiln-sections, flues at the ends of the kiln-sections connecting the ovens, and means for establishing communication between said flues and a flue leading to the stack, substantially as shown.

8. In a kiln a series of ovens each having surrounding heat-chambers, flues connecting 90 said heat-chambers with a flue connected with a stack of a flue for establishing communication between the oven and the stack substantially as shown and for the purpose set forth.

95 9. In a kiln having a series of ovens arranged within the walls of the kiln so as to provide heating chambers or flues which surround the ovens furnaces communicating with said heating-chambers and with a stack, 100 flues for connecting the ovens with the flue leading to the stack and intersecting dampers for said flues substantially as shown.

10. In a kiln having a series of ovens separated by partition-walls with openings there-through, heating-chambers surrounding the sides and top of each oven furnaces communicating with said chambers a flue connecting the heat-chamber with the heat-chamber of the adjacent oven, flues below the partition-walls of the oven and in communication with said ovens and flues for connecting the same with a flue common to each of the ovens and means for establishing communication with said flue and a flue leading to the stack. 110 115

11. In a kiln the side wall having flues connecting heating-chambers which surround the ovens of the kiln with each other a series of furnaces and arches extending therefrom to the portion of the heating-chamber farthest 120 from the flue, partition-walls having openings a horizontal flue beneath the partitions, said flue connecting with a flue leading to the stack and dampers which intersect the flues substantially as shown and for the purpose 125 set forth.

In testimony whereof I have hereunto set my hand in presence of two subscribing witnesses.

HENRY W. WANAMAKER.
